UNITED STATES PATENT OFFICE.

WILLIAM ROHRBACHER, OF ERIE, PENNSYLVANIA.

COMBINATION WATER-TUBE AND FIRE-TUBE BOILER

1,174,182.

Specification of Letters Patent. Patented Mar. 7, 1916.

Application filed August 25, 1915. Serial No. 47,315.

To all whom it may concern:

Be it known that I, WILLIAM ROHRBACHER, a citizen of the United States of America, residing at Erie, in the county of Erie and State of Pennsylvania, have invented certain new and useful Improvements in Combination Water-Tube and Fire-Tube Boilers, of which the following is a specification.

10 This invention relates to certain new and useful improvements in combination fire tube and water tube boilers, and has for one of its objects the provision of a boiler in which the travel of the water circulation is 15 in the same direction as the flue gases, and in which a positive circulation of the water is assured.

Another object of the invention is the provision of a combined fire tube and water tube boiler so constructed as to assure a maximum evaporation due to the utilization of all the heat, a resultant drier steam and consequent increased capacity boiler without increasing the size of the boiler.

25 A still further object of the invention is the provision of a combined fire tube and water tube boiler so constructed as to provide, in the boiler, the advantage of an economizer, rendering the employment of 30 an economizer unnecessary.

Still another object of the invention is to provide a boiler of the type described in which the tubes discharge in a horizontal position instead of in a vertical or inclined 35 position as is the general practice in water tube boilers, thereby reducing to a minimum the chances of a slug of water in the steam line.

Still another object is to provide a boiler 40 of the type described having by reason of the construction and arrangement, a large combustion chamber, and a large steam space, desideratum much sought after in boiler construction, and also a construction 45 which results in the elimination of all dead water in the boiler.

Still another object of the invention is to provide a boiler in which the number of repair parts are reduced to a minimum, in 50 which all parts are readily accessible, and which can be fixed with different forms or styles of furnace as may be desired; furthermore, a boiler in which all parts which come 55 in contact with the fire or furnace gases are covered with water, assuring same against burning.

With the above general and other specific objects in view which will hereinafter more fully appear as the invention is more fully described and claimed, the invention consists in the novel construction, combination and arrangement of parts as will appear from the detail description of a practical and preferred embodiment of the invention as disclosed in the accompanying drawings 60 forming a part of this specification and wherein like numerals of reference are used to designate like parts throughout the different views in which:—

Figure 1 is a central vertical sectional view of a boiler in accordance with my invention, the boiler being broken away, as is also one of the firing furnaces or ovens, and connection with the stack or flue being omitted. Fig. 2 is a horizontal sectional view of a boiler in accordance with this invention, looking toward the furnace or ovens on line II—II of Fig. 1. Fig. 3 is a view in elevation on a reduced scale showing the connection with the stack or flue, the latter being broken away, and Fig. 4 is a view in plan partly broken away and partly in section, on the same scale as Fig. 3, showing a circular furnace for firing in lieu of the Dutch ovens shown in Figs. 1 and 2. 85

The embodiment of the invention as herein shown comprises an upper or top drum 5 mounted in the top of the boiler setting 6 and extending above said setting and down into the chamber within the boiler setting. 90 This upper drum 5 is connected to a bottom drum 7 by the large centrally disposed tube 8 that is riveted or otherwise secured at its upper end to the lower end of the top drum 5, and at its lower end to the upper end of 95 the bottom drum 7.

An extension 9 is secured, as by tap bolts or studs onto the lower end of the tube 8 and extends downwardly some distance into the bottom drum 7 for the purpose of carrying the water circulation well toward the bottom of the drum 7. This tube extension 9 is preferably made in three parts and bolted together vertically so that it can be easily taken out for repairs or for cleaning the bottom of drum 7. Holes 10 near the top of the extension tube 9 are provided for the purpose of allowing any vapor that may accumulate near the top of drum 7 to escape into the extension 9 and tube 8, thereby preventing the formation of a steam pocket 110 in the top of drum 7.

Water tubes 11 are arranged in spaced rows around the circumference of the projecting lower end of the top drum 5 and the upper portion of the bottom drum 7 to which drums the respective ends of said tubes are secured and the connections made steam and water tight in the usual manner.

The water tubes 11 surround a central baffle wall 12, said tubes being located in the space 14 between the baffle wall 12 and the boiler setting 6, the central baffle being supported upon a cast iron shoe 15 that extends around the upper end of the bottom drum 7.

15 The fire tubes 16 are all arranged in the bottom drum 7, their upper or inlet ends communicating with the space 17 between the baffle wall 12 and central large tube 8.

20 The boiler may be fixed by means of one or more Dutch ovens 18, as shown in Figs. 1 and 2 or with one circular furnace 18' extending all around the boiler as shown in Fig. 4. I do not therefore limit myself as to the nature or form of furnace employed in connection with the boiler improvement. The bottom drum 7 is supported by lugs 19 riveted or otherwise secured to the outside of the drum on each quarter.

30 20 represents a perforated baffle plate in the top drum 5.

21 represents the stack or outlet flue.

35 A space 21' is provided at one side to take out and replace tubes and also to enable cleaning of the combustion chamber. This space in practice is at the point where the drums are joined by butt straps, through which the tubes cannot be extended.

40 In operation, furnace gases from the furnace or furnaces passes up the space 14 between walls 6 and 12 to the top drum 5 and then down the space between the baffle wall 12 and large center tube 8, through fire tubes 16 to the usual tunnel or space 45 (indicated at 22, Fig. 3 under the boiler) and thence to the stack or chimney. Thus, at the same time, the water contained within the drum 7 is being subjected to the heating action of the tubes 16, and the water in tubes 11, drum 5 and tube 8 is being subjected to the heating action of the furnace gases as the latter circulate through the boiler to the outlet at the bottom of the same.

50 55 By this construction I obtain a positive circulation of the water, traveling in the same direction as the flue gases and a resultant greater evaporation due to the utilization of all the heat units. The fire tubes arranged in the bottom drum answer the same purpose as an economizer rendering the use of an economizer unnecessary. I desire to call attention to the fact that with the construction shown and described a very large combustion chamber is provided, and 60 also a large liberating space, as all the water

tubes discharge around the circumference of the top drum. Owing to the fact that the water tubes extend horizontally at their upper ends and thus discharge the water horizontally instead of vertically as is usual in water tube boilers the chances of getting a slug of water in the steam line is reduced to a minimum. The top drum provides a large steam space, and no dead water obtains, as the circulation is carried to the bottom of the lower drum.

70 The device is extremely simple in its construction, and all that is needed to erect at the plant is a flue expander and beading tool, as all rivets are driven in the shop. This renders the boiler easy to ship and handle. No bracing is required for the top drum and but a small space in the bottom drum need be braced. All parts that come 75 in contact with the fire or furnace gases are covered with water thereby reducing the chances of required repairs to the minimum. It is to be noted that the water tubes are of different lengths, but of the same shape while the fire tubes are all of the same size and shape, so that there are the smallest possible number of repair parts required.

80 85 The embodiment here shown is of a furnace of circular form and described accordingly. It is to be understood however that I do not so limit myself as to shape but that this and other features may be altered and changed without departing from the spirit and scope of the invention as disclosed and claimed.

90 95 What I claim is:—

100 105 1. In a combined water tube and fire tube boiler, a top drum and a bottom drum, a tubular member connecting the drums, a cylindrical baffle wall supported at its lower end on the lower drum and spaced at its upper end from the upper drum, water tubes connecting said drums and spaced outwardly of the baffle wall, and fire tubes extending through the bottom drum and communicating at their upper ends with the chamber afforded by the baffle wall.

110 115 2. In a combined water tube and fire tube boiler, a top drum and a bottom drum, a tubular member connecting the same, water tubes connecting said drums around the circumference, a baffle wall positioned between said tubes and tubular member and extending substantially the entire lengths thereof, said tubes having curved upper ends leading into the top drum in a horizontal plane, and fire tubes in the bottom drum positioned inwardly of the baffle wall.

120 125 3. In a boiler of the type described, a top drum and a bottom drum, a central combustion chamber between the drums and communicating at its upper end with a lateral combustion chamber, and water tubes connecting said drums arranged in said lateral chamber and in communication with

the central chamber adjacent their upper ends, the tubes leading into the top drum in a horizontal plane.

4. In a boiler of the type described, a top 5 drum and a bottom drum, a plurality of water tubes connecting the confronting ends of said drums around their circumference, a central tubular member connecting the drums, and an extension carried by said 10 member extending downwardly into the bottom drum with the lower end thereof disposed parallel to the lower end of the bottom drum and spaced therefrom.
5. In a boiler of the type described, a top 15 drum and a bottom drum, water tubes connecting the drums around their circumference, said tubes leading into the top drum in a horizontal plane, a central tubular member connecting the drums, a baffle surrounding said member and extending upwardly from the lower to a point adjacent the upper drum and slightly spaced therefrom, an extension carried by the tubular member and extending downwardly into the 20 lower drum and spaced from the lower end thereof, and fire tubes in the lower drum surrounding said extension and communi-

cating at their upper ends with the combustion chamber spaced inwardly of the baffle.

6. In a boiler of the type described, upper 30 and lower communicating drums, heat deflecting means extending from the lower drum to a point adjacent the upper drum, and connecting tubes between the drums spaced outwardly of the heat deflecting 35 means.

7. In a boiler of the type described, a top 40 drum and a bottom drum, a tubular member connecting the confronting ends of said drums centrally of said ends, a baffle surrounding said member and extending upwardly from the lower end thereof to a point adjacent the upper end, water tubes connecting the drums, said tubes lying in the space between said baffle and the boiler 45 setting, an extension carried by the central connecting member and extending downwardly into said bottom drum, and fire tubes in the bottom drum around said extension and communicating at their upper ends with 50 the chamber within the baffle.

In testimony whereof I affix my signature.

WILLIAM ROHRBACHER.
